DESIGN FOR A COMBINED ILLUMINABLE
CLOCK, TELEPHONE STAND, AND CALEN-
DAR

Mary J. Brusseau, Detroit, Mich.

Application November 22, 1946, Serial No. 135,021

Term of patent 14 years

(Cl. D42—7)

To all whom it may concern:

Be it known that I, Mary J. Brusseau, a citizen of the United States, residing in Detroit, Wayne County, Michigan, have invented a new, original, and ornamental Design for a Combined Illuminable Clock, Telephone Stand, and Calendar, of which the following is a specification, reference being had to the accompanying drawing, forming part thereof.

Fig. 1 is a front elevational view of a combined illuminable clock, telephone stand, and calendar, showing my new design, the printed matter shown by the calendar being merely representative of that which would appear thereon from time to time.

Fig. 2 is a side elevational view of the disclosure of Fig. 1.

I claim:

The ornamental design for a combined illuminable clock, telephone stand, and calendar, as shown and described.

MARY J. BRUSSEAU.
